US0D1029819S

(12) **United States Design Patent** (10) **Patent No.:** **US D1,029,819 S**
(45) **Date of Patent:** **** Jun. 4, 2024**

(54) **CELLPHONE BRACKET**

(71) Applicant: **NINGBO LEDE COMPUTER TECHNOLOGY CO LTD.**, Zhejiang (CN)

(72) Inventor: **Yuman Lou**, Zhejiang (CN)

(73) Assignee: **NINGBO LEDE COMPUTER TECHNOLOGY CO., LTD**, Zhejiang (CN)

(**) Term: **15 Years**

(21) Appl. No.: **29/833,543**

(22) Filed: **Apr. 5, 2022**

(30) **Foreign Application Priority Data**

Oct. 11, 2021 (CN) 202130665591.5

(51) **LOC (14) Cl.** **13-02**

(57) **CLAIM**

The ornamental design for a cellphone bracket, as shown and described.

DESCRIPTION

FIG. 1 is a front upper perspective view illustrating a cellphone bracket showing my new design;

FIG. 2 is a rear upper perspective view thereof;

FIG. 3 is a rear lower perspective view thereof;

FIG. 4 is a front elevation view thereof;

FIG. 5 is a rear elevation view thereof;

FIG. 6 is a left-side elevation view thereof;

FIG. 7 is a right-side elevation view thereof; and,

FIG. 8 is a top plan view thereof.

1 Claim, 8 Drawing Sheets
